UNITED STATES PATENT OFFICE.

EDWIN P. FRYE, OF MILBURN, WEST VIRGINIA.

INVALID'S BED.

1,345,760.

Specification of Letters Patent. Patented July 6, 1920.

Application filed February 5, 1919. Serial No. 275,129.

To all whom it may concern:

Be it known that I, EDWIN P. FRYE, a citizen of the United States, residing at Milburn, in the county of Fayette and State of

5 West Virginia, have invented certain new and useful Improvements in Invalids' Beds; and I do hereby declare the following to be a full, clear, and exact description of the invention, such as will enable others skilled 10 in the art to which it appertains to make and use the same.

This invention relates to invalids' beds and the primary object of the invention is to provide an improved bed for invalids 15 and the like, which is so constructed, that the body portion thereof can be folded so as to form a seat.

Another object of the invention is to provide an improved hospital or invalid's bed, 20 having an improved means for raising and lowering the different sections of the body portion thereof to form a seat, so that the same may be conveniently and quickly adjusted.

25 A further object of the invention is to provide an improved hospital or invalid's bed formed of a plurality of hinged sections, which are adapted to be brought into alinement with each other to form a bed, or 30 adjusted with relation to each other to form a reclining seat or chair.

A still further object of the invention is to provide improved means for connecting the springs to the hinged sections of the bed, so that when the hinged section is 35 raised or lowered, the spring will conform to the configuration thereof.

A still further object of the invention is to provide an improved invalid's bed of the 40 above character, which is durable and efficient in use, one that is simple and easy to manufacture, and one that can be placed upon the market at a reasonable cost.

With these and other objects in view the 45 invention consists in the novel construction, combination and arrangement of parts, as will be hereinafter more specifically described, claimed and illustrated in the accompanying drawings forming a part there- 50 of, in which:

Figure 1 is a side elevation of the improved bed,

Fig. 2 is a longitudinal section showing the body portion of the bed in its raised position,

55

Fig. 3 is a plan view of the bed,

Fig. 4 is a transverse section taken on the line 4—4 of Fig. 1.

Fig. 5 is a detail perspective view of the means for slidably connecting the parts of 60 the head and foot sections together.

Referring to the drawings in detail, wherein similar reference characters designate corresponding parts throughout the several views, the numeral 1 generally indicates the improved invalid's bed, which includes a rigid frame 2 formed of angle iron or the like, which is adapted to be supported on the bedstead 3. The rigid frame 2 includes longitudinal side bars 4 and the end 65 bars 5. The horizontal portions of the angle irons of the longitudinal side bars 4 extend over and engage the side pieces 6, which are connected to the head and foot pieces 7 and 8 in the ordinary or any preferred manner. 70 Crossed braces 9 extend diagonally across the rigid frame and brace the same against all undue strain.

An upper frame 10 is positioned above the rigid frame 2 and this frame is constructed preferably of angle iron and is of the same shape and dimensions as the lower frame. The upper frame 10 includes a plurality of hinged sections 11, 12 and 13, which form respectively the head, body and foot 80 portions of the bed. The head 11 and body portion 12 are connected at their upper edges by means of a hinge 14. The foot section 13 and the body section 12 are connected at their lower meeting edges by means of hinges 16. 90

The pivoted catches 16 are preferably carried by the terminals of the body section 12 and are adapted to engage over pins 17 carried by the adjacent ends of the head and foot sections and are to hold the sections in rigid 95 position, when the sections are in alinement with each other. The body section 12 is formed of side pieces 18 and the head and foot sections 11 and 13 are formed of side pieces 19 and end pieces 20. The side pieces 100 19 are each formed of two sections 21 and 22, which are slidably connected together. The section 21 has one end thereof reduced as at 23 and provided with slots 24 and the

section 22 is positioned over the reduced extension 23 and carries bolts 25 which are slidably received in the slots 24. Suitable nuts 26 are threaded on the bolts to hold the sections against movement when so desired. The purpose of forming the head and foot sections in two parts, will be hereinafter more fully set forth. The end pieces 20 and side pieces 19 of the hinged sections are connected by diagonal braces 27 which hold the same against distortion.

A spring 28 is secured to the upper frame 10 and includes contractile coil springs 29 which have their outer terminals secured to 15 the end pieces 20 of the head and foot sections 11 and 13. The inner ends of the coil springs are connected by links 30 and at suitable distances between the end pieces contractile coil spring 31 are inserted 20 between the links 30. Cross links 32 connect the links 30 together and the outer links 32 are connected to the side bars 18 and 19 of the head, foot and body portions of the upper section 10. Depending links 33 are connected to the links 30 and are extended 25 around bars 35, which extend transversely across the head and foot sections adjacent to the meeting ends thereof, and across the body section adjacent to its inner end. The 30 links 33 encircling the bars 35 permit the spring to conform to the configuration of the frame, when the sections thereof are raised or lowered.

Suitable braces 36 extend transversely 35 across the upper frame 10 and have the terminals thereof bent upwardly to provide feet 37, which are secured to the vertical portions of the side bars of the head, foot and body sections. These brace bars 36 are 40 positioned adjacent to the outer ends of the head and foot sections and adjacent to the rear end of the body section and these braces have secured to the lower surfaces thereof depending studs 38 having spaced 45 ears 39 between which are positioned the reduced ends 40 of the threaded bars 41. Suitable pivot pins 42 extend through the studs and the reduced ends 40 of the threaded bars. Bearing blocks 42' are secured to the upper surface of the side bars 4 of the lower frame 2 adjacent to the outer end thereof and approximately two-thirds of the distance from the head to the foot and these bearings rotatably support the shafts 50 43 which extend transversely across the lower frame. These shafts carry worm screws 44 which mesh with worm wheels 45 mounted upon the threaded bars 41. The worm wheels 45 are carried by bearing 55 blocks 46, which include a base plate 47, a vertical section 48 and an overhanging horizontal portion 49. The base plate 47 supports a bearing 50, which receives the shafts 43. The overhanging portion 49 and the 60 base plate 47 are provided with alined aper-

tures which rigidly receive the threaded bars 41 and the worm wheel 45 is confined between the overhanging portion 49 and the base plate 47. The bearings 46 are secured to the side bars 4 by any suitable means, 70 such as bracket 46'. The ends of the shafts 43 are squared as at 52 and detachably fitted on the squared ends are cranks 53, which form means for rotating the shafts.

When it is desired to have the patient sit 75 up or in a reclining position, the cranks 53 are rotated, so as to turn the shafts 43, which through the medium of the worm 44, and the worm wheels 45, will elevate the threaded bars 41 and thus elevate the head, body and foot sections. Each shaft is rotated as much as desired so as to position each section in the desired place. The head and foot sections are made in two parts, so that when the same are raised or lowered 80 the parts will spread so to allow the upper ends of the threaded rods to be at all times positioned directly over the boxes 46.

The upper frame 10 may also be raised, when so desired, when the sections are all in 90 alinement with each other.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, proportion and arrangement of parts may be resorted to, when required without sacrificing any of the advantages of my invention as set forth.

What I claim as new is:

1. An invalid's bed comprising a lower rigid frame, an upper frame formed of a plurality of hinged sections, depending threaded rods carried by each section, transverse shafts carried by the lower frame and positioned one below each section, boxings secured to the frame for receiving the shafts, worm wheels carried by the boxings and mounted respectively upon said threaded rods, and worm screws mounted 110 on shafts for engaging said worm wheels, as and for the purpose specified.

2. An invalid's bed comprising a lower rigid frame, an upper frame including head, foot and body sections, means hingedly connecting the meeting ends of the sections together, depending threaded bars carried by each section, means carried by the lower frame for receiving and adjusting each threaded bar, the head and foot sections of the upper frame being formed of slidably connected portions to allow for contraction or extension of these sections as the threaded bars are adjusted, as and for the purpose specified.

3. An invalid's bed comprising a lower frame, an upper frame formed of a plurality of hingedly connected sections, depending threaded bars carried by each section, 5 means carried by the lower frame for receiving the threaded bars, a continuous bed spring carried by the upper frame, and means carried by the inner ends of the sections for engaging said spring, so as to 10 cause the spring to conform to the configura-

tion of the sections, when the same are raised or lowered by means of the threaded bar.

In testimony whereof I affix my signature in presence of two witnesses.

EDWIN P. FRYE.
